(57) **CLAIM**

The ornamental design for an automotive floor rear mat, as shown and described.

DESCRIPTION

FIG. 1 is a top, right and rear side perspective view of an automotive floor rear mat, showing my new design;

FIG. 2 is a bottom and rear side perspective view thereof;

FIG. 3 is a top plan view thereof; and,

FIG. 4 is a bottom plan view thereof.

The broken lines shown in the drawings illustrate portions of the automotive floor rear mat that form no part of the claimed design.
